UNITED STATES PATENT OFFICE.

AUGUST KOTTMANN, OF SOMMERDA, GERMANY, ASSIGNOR TO RHEINISCHE METALL-WAAREN- UND MASCHINENFABRIK, OF DUSSELDORF-DERENDORF, GERMANY.

TOTAL AND SUBTOTAL MECHANISM.

Application filed December 17, 1925, Serial No. 75,917, and in Germany December 30, 1924.

This invention relates to a device for automatically printing totals and sub-totals in calculating and adding machines of the recording type, and particularly to a device for 5 this purpose of the kind in which the tens carrying levers are locked during the depression of a sub-total key.

The object of the invention is to provide a reliable locking device of simple construction, this purpose being achieved by arranging the sub-total key to act through a bell-crank lever to lock a pawl which is adapted to be actuated by a cam of the cam-disc serving to disconnect the coupling wheels, said 15 pawl, when released by depression of the sub-total key, locking the lever controlling the coupling wheels in their position of engagement.

The invention is illustrated, by way of 20 example, in the accompanying drawing, in which:

Fig. 1 is a perspective view of the new device,

Fig. 2 is a perspective view showing some 25 of the details thereof in the positions assumed when the total key is depressed, and

Fig. 3 is a perspective view with the several parts in the positions assumed when the sub-total key is depressed.

30 A shaft 35, mounted in the frame 34 of the calculating or adding machine, adapted to be rotated, for example, by means of a crank handle 1, carries a cam disc 4, provided with a cam 32, and a second cam 33. 35 The cam 32 coats with a pivotally mounted lever 2, controlled by a spring 11, a lug 6 on which embraces the shaft 7 carrying the coupling wheels 8, and is adapted to displace said shaft, together with the wheels 8, in 40 order to couple the racks 9 with the pinions of the numeral wheels 10. A lever 28, controlled by a spring 31 (Fig. 3) is mounted on the frame 34, one end of this lever being adapted to be brought within the range of 45 movement of the cam 33, whilst the other end is normally locked by a bell-crank lever 36, connected with the sub-total key 39 by means of a rod 37 and a spring-controlled bell-crank lever 38. The lever 28 carries a lug 50 40 adapted to be brought into engagement with the lever 2 in order to lock this latter in a determined position. The transfer levers 17 for the tens are provided, in the usual manner, with lugs 20, and are adapted 55 to rotate on an intermediate shaft 12 suit-

ably arranged in the machine. The lugs 20 coat with lugs 19 on the numeral wheels 10, in order to transfer the tens. Within reach of the movement of the transfer levers 17 is arranged a locking member, such as a rail 60 14, which is normally held, by the action of a spring 42, in such a position that it does not interfere with the rocking movement of the said levers 17. The total key 41 is provided with a sloping cam surface 13, which 65 comes in contact with the rail 14 when the key is depressed, and displaces said rail, against the action of its spring 42, in such a way as to check the rocking movement of the levers 17. This position of the various 70 parts is represented in Fig. 2; in the said position, the lugs 20 of the levers 17 act as stops for the lugs 19 of the wheels 10. The racks 9 at their ends are provided, in the well known way, with type carriers of conventional form, the types of which are operated by means of pressure hammers in the well known manner; the type carriers and pressure hammers have been omitted from 75 the drawing for the sake of clearness. The 80 values set up in the printing mechanism are imprinted upon a sheet of paper supported upon a printing platen of recognized form, these elements also not being illustrated in the drawing. The said type carriers, pressure 85 hammers, and printing platen form no part of the present invention.

The operation of the device is, briefly, as follows:—

When the calculating operation is terminated and the numeral wheels indicate the final result—for instance "12", as shown in the drawing—the key 41 is then depressed, so that the various parts occupy the position shown in Fig. 2; that is to say, the lugs 90 20 now act as stops for the lugs 19 of the numeral wheels 10. If the handle 1 be now turned, to operate the machine, the coupling wheels 8 are brought into operation through the combined action of the cam 32 and lever 95 2, so that the racks 9 are connected with the pinions of the wheels 10. At the instant the coupling is effected, the racks 9 move back, under the influence of the springs 18, so that, in reality, the result "12" is taken out of the 100 machine; that is to say, the wheels 10 run back until their lugs 19 strike against the now stationary lugs 20 of the lever 17. As 105 soon as the lever 2 again comes out of engagement with the cam 32, and the coupling 110

wheels 8 are thereby again disengaged, the racks 9 are returned to their original position, by any suitable means, against the action of the springs 18, the wheels 10 remaining set at zero. As soon as the handle has completed a full turn, the key 41 rises automatically, thus causing the various parts to resume the position shown in Fig. 1, ready for the next calculating operation.

If a sub-total is to be printed, the key 39 is depressed, whereupon, by means of inter-engaging lugs on the keys 39 and 41 (see Fig. 1) the key 41 is depressed, and by means of cam 13 the rail 14 is brought into the position shown in Fig. 2, so that the transfer levers 17 for the tens again serve as fixed stops for the lugs 19 of the rollers 10. At the same time, the key 39 acts on the bell-crank lever 38, so that, through the agency of the rod 37, the bell-crank lever 36 is turned on its pivot and releases the end 29 of the lever 28, which then moves downward under the action of its spring 31, its lug 40 preventing the retraction of the lever 2, previously swung out by the cam 32. The consequence is that the value "12", now present in the machine, is first cancelled by the return movement of the racks 9 and then brought back into the original position in the machine, by the movement of the racks 9. On continuing to turn the handle 1, the cam 33 is finally brought into position underneath the lever 28, thereby lifting the latter against the action of its spring 31, so that the lever 2 is now able to swing back again,

and the bell-crank lever 36 can again engage over the free end 29 of the lever 28 on the ascent of the key 39.

What I claim and desire to secure by Letters Patent is:—

In a calculating machine the combination of numeral-wheels, tens carrying levers controlling said numeral-wheels, operating racks, coupling wheels normally disconnected from said numeral-wheels, a pivoted lever 40 operatively connected with said coupling wheels, a cam-disk adapted to operate said pivoted lever to shift said coupling wheels into operative connection with said numeral-wheels, a locking lever arranged to lock said pivoted lever against operation to disengage said coupling wheels from said numeral wheels, a depressible sub-total key, means for locking said carrying levers in fixed position upon depression of said key, a retaining bell-crank lever for normally maintaining said locking lever in an inoperative position, bell-crank mechanism controlled by said sub-total key and connected with said retaining lever for shifting said locking lever, upon said depression of said sub-total key, to release said locking lever and permit it to assume its operative locking position to lock said pivoted lever against operation, and means on said cam-disk for shifting 55 said locking lever back to its inoperative position.

In testimony whereof I have affixed my signature.

AUGUST KOTTMANN.
